UNITED STATES PATENT OFFICE.

JOSEPH R. PAYSON, JR., OF CHICAGO, ILLINOIS.

ATTACHMENT FOR FLOUR-BARRELS.

SPECIFICATION forming part of Letters Patent No. 332,105, dated December 8, 1885.

Application filed April 3, 1885. Serial No. 161,105. (No model.)

To all whom it may concern:

Be it known that I, JOSEPH R. PAYSON, Jr., a citizen of the United States, residing in Chicago, in the county of Cook and State of Illinois, have invented a new and useful Improvement in Attachments for Flour-Barrels, of which the following is a specification.

Heretofore flour sifters and measurers have been used by hand separately either at the time of taking the flour from the barrel or subsequently. Boxes or chests adapted to be filled with flour and provided with spouts at their under sides or bottoms, through which the flour may be sifted or measured, have also been employed. These chests or boxes, however, form special articles of manufacture, and the sifters or spouts used on them are not capable of being applied to the original barrels in which the flour is bought, but the flour must be transferred to the chests.

The object of my invention is to provide a barrel-head which may be readily applied to the ordinary flour-barrel, whereon it may be inverted after being opened, and through an opening in which the contents of the barrel may be conveniently withdrawn as they are wanted; and this head may be provided with a sifter or measurer, or both, so that the withdrawing and sifting, or the withdrawing, sifting, and measuring become simultaneous operations. These and other features of the invention will be more fully understood from the following description and the accompanying drawings, wherein—

5 Figure 1 is a plan of my invention. Fig. 2 is a central vertical section of the same upon the line 2 2 of Fig. 1. Fig. 3 is a like section showing a modification. Fig. 4 is a like section upon line 4 4 of one half the attachment shown in Fig. 1, the other half being shown in elevation. Fig. 5 is a view, partly in section and partly in elevation, of the modification, Fig. 3. Figs. 6 and 7 show a measuring device attached to the head, the 40 first being a section and the other partially a section and front elevation.

In said drawings, A represents an ordinary flour-barrel, the open end whereof is shown. B represents a platform, serving as a head 45 temporarily for the said open end of the barrel. It may be a plane, flat surface, or hopper-shaped, as shown, the latter being pref-

though not so economical in manufacture. At the center of this head is a discharge-opening, b, through which the flour is withdrawn as it 55 is needed, and such opening may be closed by a simple gate, C, or a sifter, D, may also be placed in it, or the sifter alone may be employed, as the flour will not ordinarily fall through the opening guarded by a sifter unless 60 agitated or shaken.

To make my removable or attachable head fit the barrel, I provide it with an upstanding rim, E, and to make the joint between the two tight I preferably insert within the rim a 65 rubber packing-ring, E', such ring being attached to the rim in some suitable manner. The head may be attached to the barrel by thumb-screws f in the strap-pieces F, secured to the head in any appropriate manner. 70

The platform may be provided with legs G, so that it will act to support the barrel at a convenient remove from the floor, and casters g may also be employed, if preferred.

In the modification, Fig. 3, the platform or 75 head is supported upon a box or inclosed stand, H, having a drawer, h, to receive the flour, or a pan or other receptacle to be supplied therewith. In this case a sliding gate, h', of the same horizontal dimensions as the drawer, or smaller, 80 may be used to prevent any discharge when the drawer is pulled out. The wires d d serve as the stationary part of the sifter in the sifting operation. Handles m should be provided for both the gate and sifter. 85

In Figs. 6 and 7 the discharge-opening is continued downward, and two slides, C C, inserted therein, that portion of the discharge between said slides, and lettered C', being constructed to hold some predetermined quantity 90 of the flour.

Although I have described a sifter and temporary head to be applied to the open end of a barrel, and fastenings for attaching to the barrel, as well as supports for the same, I wish 95 it understood that the particular construction of none of these is of the essence of my invention, and the same is true of the measurer.

In the use of my invention it will be found convenient to apply the head to the barrel before the latter is inverted.

I claim—

1. As a new manufacture, a combined gated flour-barrel head and stand adapted to be ap-

- erable for the better discharge of the flour, applied to the barrel before it is inverted and to support it after inversion, substantially as and for the purpose set forth.
5. 2. As a new manufacture, a combined gated flour-barrel head and stand adapted to be applied to the barrel before it is inverted and to support it after inversion, and provided with a sifter, substantially as specified.
10. 3. As a new manufacture, a gated flour-barrel head and stand provided with a measuring device, substantially as specified.
4. As a new article of manufacture, an improved barrel-head provided with means for securely attaching it to the barrel, and having a gated opening and supports, the whole being adapted to be applied as a barrel head to an open flour-barrel before inversion, and to permit the barrel to be inverted without spilling the contents, substantially as specified.
20. 5. A united barrel-head, sifter, and barrel-stand adapted to be securely attached to an open barrel before inversion, substantially as specified.

JOSEPH R. PAYSON, JR.

NAT. J. BAUR.

It is hereby certified that in Letters Patent No. 332,105, granted December 8, 1885, to Joseph R. Payson, jr., for an improvement in "Attachments for Flour Barrels," an error appears in the printed specification requiring correction as follows: The part of a word and the words "erable for the better discharge of the flour," which now appear as the first line in column 1, page 2, should be transferred to and become the first line of column 2, page 1; and that the specification should be read with this correction therein that the same may conform to the record of the case in the Patent Office.

Signed, countersigned, and sealed this 22d day of December, A. D. 1885.

[SEAL.]

H. L. MULDROW,
Acting Secretary of the Interior.

Countersigned:

R. B. VANCE,

Acting Commissioner of Patents.
